(57) **CLAIM**

The ornamental design for a multipurpose cutting tool, as shown and described.

DESCRIPTION

FIG. 1 is a top front perspective view of a multipurpose cutting tool, showing my new design;

FIG. 2 is a left side elevation view thereof, the right side elevation view being a mirror image thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a top perspective view thereof, shown in a storage position.

The parallel jagged broken lines shown in the drawings depict a symbolic break in the length of the multipurpose cutting tool. The portions of the multipurpose cutting tool depicted by and between the parallel jagged broken lines form no part of the claimed design. The circular broken lines shown in the drawings depict portions of the multipurpose cutting tool that form no part of the claimed design. The short broken lines shown in FIG. 7 depict a cap that is environmental subject matter and forms no part of the claimed design.
